TAPE DRAWING DEVICE

August D. Eitzen, New York, N. Y., assignor to
 News Projection Corporation, New York, N. Y.,
 a corporation of New York

Application December 28, 1928, Serial No. 329,026

14 Claims. (Cl. 178—42)

This invention relates to stock quotation projecting machines in general and more especially to devices for drawing the tape through the projecting machine.

Among the objects of the present invention it is aimed to provide improved means for drawing tape through the projector of stock quotation projecting machines according to which a continuously driven electric motor may be used, and a device whereby the tape drawing roller may be disconnected from driving connection with the electric motor.

It is still another object of the present invention to provide in combination with a stock quotation projecting machine, a magnetically controlled brake for disconnecting the tape drawing roller from driving connection with the electric motor when the ticker has finished a message and ceases to operate.

These and other features, capabilities and advantages of the invention will appear from the subjoined detail description of specific embodiments thereof, illustrated in the accompanying drawing in which

Figure 1 shows diagrammatically an embodiment of the invention in which the electric impulses of the ticker are relied upon to initiate the tape drawing action;

Fig. 2 is an elevation partly in section showing the magnetically controlled brake; and—

Fig. 3 illustrates diagrammatically a portion of another embodiment in which the slack formed in the tape is utilized to initiate the tape drawing action.

With the present invention, the tape T after leaving the ticker is caused to pass through a projector or projecting machine. This movement of the tape after it leaves the ticker is controlled by a tape drawing device which is initiated in the embodiment illustrated in Fig. 1 by the electric impulses passing through the ticker when it transmits a message.

In the embodiment illustrated in Fig. 1, the ticker 1 is provided with a plurality of magnets 2, 3, 4 and 5. The magnets 2 and 3 are connected to the connection plug 6 representing the source of telegraphic impulses by means of the electric conductor 7, which electric connection 6 is connected to the ticker switch 8 by the electric conductor 9. The other end of the magnets 2 and 3 is connected by the conductor 10 to the electric connection 11 which is connected by the conductor 12 to one end of the magnets 4 and 5. The other end of the magnets 4 and 5 is connected by the conductor 13 to the electric con-

nection 14 which is connected to the outlet plug 15 by the electric conductor 16, which outlet plug 15 is connected to the switch 8 by the electric conductor 17. The electric connections 6 and 14 are connected to the magnet 18 by the electric conductors 19 and 20 respectively. The electric magnet 18 and associated connections are provided to control the switch 21 of the magnetically controlled brake band 22.

When an electric impulse is transmitted to 10 the ticker 1, the same will energize the magnet 18 to attract the armature arm 23 pivotally mounted on the bracket 24. Fixedly secured to the armature arm 23 and insulated therefrom is the electric contact member 25 which is adapted to engage the electric contact member 26. The electric contact member 25 is connected to the outlet plug 27 by the electric conductor 28, which outlet plug 27 is connected to the magnet 29 by the electric conductor 30, and the contact member 26 is connected to the magnet 29 by the electric conductor 31.

When the armature arm 23 is attracted by the magnet 18 and the contact member 25 engages the contact member 26, the magnet 29 will be energized 25 to attract the core 32. The upper end of the core 32 is pivotally connected to the long arm 33 of the lever 34 which is fulcrumed at 35 on the bracket 36. The lever 34 is provided with a pin 37 to which one end of the brake band 22 30 is connected. The other end of the brake band 22 is connected to the pin 38 formed on the bracket 36. The lever 34 is also provided with a short arm 39 which is connected by the spring 40 to the ear 41 formed on the bracket 36 normally to actuate the lever 34 to cause the brake band 22 frictionally to engage the drum 42 to produce a braking action.

When the magnet 29 is energized and the core 32 is attracted, it will actuate the lever 34 about 40 its fulcrum 35 in opposition to the tension of the spring 40 to release the brake band 22 from the brake drum 42, thereby permitting the brake drum 42 and associated drawing roller 43 formed thereon to be driven with the clutch disc 44 fixed 45 on the shaft 45 on which the drum 42 and roller 43 are freely mounted.

The tape T is maintained in engagement with the drawing roller 43 by the pressure roller 43^a mounted on a lever 43^b which has connected 50 thereto the spring 43^c for urging the pressure roller 43^a into engagement with the tape T and thereby frictionally maintaining the tape T in engagement with the roller 43.

The shaft 45, as shown in Fig. 1, has secured 55

thereon the worm wheel 46 meshing with the worm 47 enclosed in the housing 48. The worm 47 is mounted on the shaft 49 which has secured thereon the pulley 50 which is connected to the 5 pulley 51 by the belt 52. The pulley 51 is connected to the motor shaft 53 of the motor 54. The motor 54, in the present instance, is shown as connected to the outlet plug 55 by the conductor 56 and to the resistance 57 by the conductor 58, which resistance 57 is connected to the outlet plug 55 by the conductor 59.

The brake drum 42 and drawing roller 43 are resiliently maintained in engagement with the clutch disc 44 by means of the spring 60 mounted 15 on the shaft 45 and pressing the collar 61 against the inner face of the roller 43, thereby causing the outer face of the brake drum 42 to be pressed against the clutch disc 44 adjacent thereto. For controlling the tension of the spring 60, the nut 20 62, screw-threadedly mounted on the end of the shaft 45, is provided.

The shaft 45, as shown in Fig. 2, constitutes the fulcrum for the arm 63, which is fixedly connected to the bracket 36 and base 64 on which 25 the magnet 29 is mounted. The free end of the base 64 is connected by the spring 65 with the upper end of the bracket 66 and by the spring 67 with the base 68, these springs 65 and 67 forming 30 cushions for the base 64 to ease the start and stop of the tape T. When the magnet 29 is de-energized and the spring 40 acts on the lever 34 to 35 initiate the braking action, the spring 65 will act as a buffer or cushion to cause the tape to come to rest gently.

35 In order to prevent the switch 21 being interrupted during the transmission of a message, there is provided a device for retarding the release of the armature 23 from the magnet 18. To this end, there is provided an arm 69 extending 40 from the armature 23 which is pivotally connected at its free end to the upper end of the plunger 70. The lower end of the plunger 70 has secured thereto the piston 71 which is slideably mounted in the cylinder 72. The lower end of the 45 cylinder 72 is connected to the upper end of the cylinder 72 by the passage 73. The piston 71 is provided with a passage 74 which, in the present instance, has a check valve 75 at its lower end. The cylinder 72 is supplied with oil.

50 The arm 69 is connected by the spring 76 with the base 77 to cause the same normally to press the piston 71 to the bottom of the cylinder 72 and to separate the armature 23 from the core 55 of the magnet 18. When the magnet 18 is energized and the armature 23 is attracted, the oil in the cylinder 72 will freely pass through the passage 74 into the lower end of the cylinder 72 to facilitate the expeditious movement of the 60 armature 23 and the engagement of the contact member 25 with the contact member 26. When the magnet is de-energized, aside from the natural attraction of the contact 25 to the contact 65 26 while current is passing through the same, the check valve 75 will prevent the movement of the oil from the lower end of the cylinder 72 to the upper end of the cylinder 73 through the passage 74 and cause the oil to pass from the lower end of the cylinder 72 into the upper end of the cylinder 72 through the restricted passage 78, thereby materially retarding the separation of the contact 25 from the contact 26, and at any 70 rate sufficiently retarding the same to prevent the same being separated in the interval between 75

successive impulses of the ticker during the transmission of a single message.

The movement of the oil through the passage 73 can be regulated by means of the set screw 78.

In the embodiment illustrated in Fig. 3, the tape T issues from the ticker 1 as described with regard to the embodiment of Fig. 1, but before passing to the projector 19 is engaged by the roller 80 from which the tape passes to the idler 81. The roller 80 is formed at the upper end of the 10 link 82 which is connected to the support 83 of the mercury switch 84. The base 83 is fulcrumed at 85 to the bracket 86. One terminal of the mercury switch 84 is connected by the conductor 87 to the outlet plug 88, which outlet plug 88 is 15 connected by the conductor 89 to the magnet 29 shown in the embodiment of Fig. 1, and the other terminal of the mercury switch 84 is connected by the conductor 90 to the magnet 29, the portion of the embodiment illustrated in Fig. 1 below 20 the line a—a being identical with the portion of the embodiment to be used with the embodiment illustrated in Fig. 3 but not there illustrated below the line a—a.

With the embodiment illustrated in Fig. 3, 25 when a message is transmitted by the ticker 1, the slack is formed in the tape T to permit the link 82 to descend and cause the mercury switch 84 to make contact, at which time current will pass through the conductors 89 and 90 to the magnet 30 29, energize the magnet 29 and thereby operate the lever 34, to release the brake drum 42 in the manner described with regard to the embodiment of Fig. 1.

35 On the other hand, when the ticker stops and the tape drawing roller 43 continues to draw the tape through the projector 19, it will take up the slack in the tape T eventually causing the link 82 to ascend and cause the mercury switch 84 to break contact, and thus shut off current to the 40 magnet 29, whereupon the spring 40 will be free again to cause the brake band 22 to lock the brake drum 42 against movement with the clutch disc 44.

45 It is obvious that various changes and modifications may be made to the details of construction without departing from the general spirit of the invention as set forth in the appended claims.

I claim:

1. The combination with a ticker and a circuit 50 therefor, of a tape drawing roller, a pressure roller for frictionally maintaining the tape in engagement with said drawing roller, a continuously operating electric motor, a clutch for drivingly connecting the motor with said tape drawing roller, a magnetic device for controlling said clutch, and an electric switch for controlling said magnetic device, said electric switch being operatively controlled by said ticker circuit.

2. The combination with a ticker, of a circuit 60 therefor, tape drawing means including a tape drawing roller, an idler and means for frictionally urging said idler to press the tape into pulling engagement with said roller, a continuously operating electric motor, a clutch for drivingly connecting said motor to drive said tape drawing roller, an electric switch electrically controlled by said ticker circuit to operate said switch to make contact when said ticker operates, and a magnetic device for controlling said clutch, said switch being electrically connected to said magnetic device to cause said magnetic device to be energized when said switch makes contact.

3. The combination with a ticker, of a circuit 75

for said ticker, a tape drawing device including a tape drawing roller and a pressure roller for frictionally maintaining the tape in drawing engagement with said roller, an actuating device, a clutch for drivingly connecting said actuating device to said tape drawing roller, and means operatively controlled by said ticker circuit for controlling said clutch.

4. The combination with a ticker, of a circuit for said ticker, a tape drawing device including a tape drawing roller and a pressure roller for frictionally maintaining the tape in drawing engagement with said roller, an actuating device, a clutch for drivingly connecting said actuating device to drive said tape drawing roller, and magnetic controlling means controlled by said ticker circuit for controlling said clutch.

5. The combination with a ticker, of a circuit for said ticker, a tape drawing device including a tape drawing roller and a pressure roller for frictionally maintaining the tape in drawing engagement with said roller, an actuating device, a clutch for drivingly connecting said actuating device to drive said tape drawing roller, magnetic controlling means controlled by said ticker circuit for controlling said clutch, and means cooperating with said magnetic controlling means to facilitate the gradual stopping of the tape drawing device and in turn the gradual acceleration of the tape drawing device.

6. The combination with a ticker, of a circuit for said ticker, a tape drawing roller, a brake drum associated with said roller and adapted to anchor said roller against movement, an actuating device, a frictional clutch for operatively connecting said actuating device to said brake drum, a brake band for said brake drum normally adapted to anchor said brake drum and therewith said roller against movement by said actuating device, and magnetic means for releasing said brake band operatively connected to said ticker circuit to be dependent for its action upon the stopping and starting of said ticker.

7. The combination with a ticker, of a circuit for said ticker, a tape drawing device including a tape drawing roller and a pressure roller for frictionally maintaining the tape in drawing engagement with said roller, an actuating device, a clutch for drivingly connecting said actuating device to drive said tape drawing roller, magnetic controlling means for controlling said clutch, an electric switch for controlling said magnetic controlling means, a switch controlling device, and electric conductors operatively connecting said switch controlling device with said ticker circuit in turn to control said magnetic controlling device.

8. The combination with a ticker, of a circuit for said ticker, a tape drawing device including a tape drawing roller and a pressure roller for frictionally maintaining the tape in engagement with said roller, an actuating device, a clutch for drivingly connecting said actuating device to drive said tape drawing roller, magnetic controlling means for controlling said clutch, an electric switch for controlling said magnetic controlling means, a magnet associated with said ticker circuit for controlling said switch, a slow motion device for retarding the separation of said electric switch when once closed, and electric

conductors for electrically connecting said switch to said magnetic controlling means.

9. The combination with a ticker, of tape drawing means, an electric motor, a clutch for operatively connecting said motor to drive said tape drawing means, an electric switch, a relay operatively associated with said ticker to actuate said switch to make contact when said ticker operates, and a magnetic device for controlling said clutch, said switch being electrically connected to said magnetic device to cause said magnetic device to be energized when said switch makes contact.

10. The combination with a ticker and a circuit therefor, of a tape drawing means, means for controlling the actuation of said tape drawing means including an electric switch, means including said ticker circuit for closing said switch when a message is transmitted to said ticker to close said ticker circuit, and retarding means for delaying the opening of said switch for an interval after the current to the ticker circuit is again opened.

11. The combination with a ticker and a circuit therefor, of a tape drawing means, means including an electric switch for controlling the actuation of said tape drawing means, means including the circuit of said ticker for closing said switch when a message is transmitted to said ticker to close said ticker circuit, and means for delaying the opening of said switch for an interval of time after it has once been closed.

12. The combination with a ticker, of a tape drawing device including a tape drawing roller and a pressure roller for frictionally maintaining the tape in drawing engagement with said roller, an actuating device, a clutch for drivingly connecting said actuating device to drive said tape drawing roller, magnetic controlling means for controlling said clutch, and an electric switch operatively associated with said ticker to be affected according as said ticker is arrested or in operation, said switch being electrically connected to said magnetic device to cause said magnetic device to be energized when said switch makes contact.

13. The combination with a ticker, of tape drawing means, a continuously operating electric motor, a clutch for operatively connecting said motor to drive said tape drawing means, an electric switch including a fixed contact and a movable contact, the movable contact being operatively associated with said ticker to be actuated according as said ticker is arrested or in operation, and a magnetic device for controlling said clutch, said switch being electrically connected to said magnetic device to be energized when said switch makes contact.

14. The combination with a ticker, of tape drawing means, a continuously operating actuating device, a clutch for operatively connecting said actuating device to drive said tape drawing means, and an electromagnet circuit including an electric switch for controlling said clutch, said switch including a fixed contact and a movable contact, the movable contact being operatively associated with said ticker to be actuated according as said ticker is arrested or in operation.

AUGUST D. EITZEN.
